UNITED STATES PATENT OFFICE.

STANISLAW KUCZYNSKI, OF CLEVELAND, OHIO, ASSIGNOR OF ONE-HALF TO
WŁADYSLAWA GRUCHACZ, OF CLEVELAND, OHIO.

TABLE ATTACHMENT FOR BEDS.

Application filed June 20, 1921, Serial No. 479,018. Renewed April 14, 1922. Serial No. 552,391.

To all whom it may concern:

Be it known that I, STANISLAW KUCZYNSKI, a citizen of the United States of America, residing at Cleveland, in the county of 5 Cuyahoga and State of Ohio, have invented certain new and useful Improvements in Table Attachments for Beds, of which the following is a specification.

This invention relates to certain new 10 and useful improvements in table attachments for beds and has particular reference to the mounting of a table upon a series of levers with the table movable to a position overlying the bed and in proximity thereto when in operative position, and capable of being shifted to lie adjacent the outer side of one end of the bed when out of use.

The primary object of the invention is to 20 provide a table attachment for beds wherein a series of levers for supporting a table are adjustably secured to the side rails of a bed with the table occupying a horizontal position above the bed when in use and capable 25 of being shifted to a position outwardly to one end of the bed when out of use, the mounting for the table providing a rigid structure so that the table is securely disposed above the bed, the table top occupying 30 a perpendicular position adjacent the end of the bed so as to occupy a minimum of space.

With the above general objects in view and others that will appear as the nature 35 of the invention is better understood, the same consists of the novel form, combination and arrangement of parts hereinafter more fully described, shown in the accompanying drawings and claimed.

40 In the drawings, wherein like reference characters designate corresponding parts throughout the several views,

Figure 1 is a side elevational view of a table attachment for beds constructed in accordance with the present invention, the same being shown as attached to a bed and illustrated by dotted lines in its inoperative position,

Figure 2 is a vertical cross sectional view 50 taken on line II—II of Fig. 1 showing the screw clamps for anchoring the table attachment to the bed,

Figure 3 is a detail sectional view taken 55 on line III—III of Fig. 1 showing the extensible rod connection between the table

and the anchoring clamp for the supporting structure.

Figures 4 and 5 are detail perspective views of the extensible connecting rod, and

Figure 6 is a detail perspective view of 60 the anchoring clamp.

Referring more in detail to the accompanying drawings there is illustrated a table 65 adjustably connected to a bed embodying side rails 1 and end members 2.

The table attachment embodies four 70 clamps, two of each being secured to the opposite side rails 1, the clamps being designated by the reference numerals 3 having bent upper ends 4 overlying the rails 1 and lateral brackets 5 through which clamping screws 6 are threaded for anchoring the clamps to the rails as shown in Fig. 2. A lever

7 is pivoted as at 8 to the clamps 3 adjacent one end of the bed and have their upper ends 75 pivoted to the table 9, in a manner to be later described. Extensible link members embodying bars 10 and 11 are arranged at opposite sides of the bed, the upper ends of which are connected to the table 9 while the lower ends of the sections 10 are laterally offset to provide mounting lugs 12 provided with openings 13 through which pivot pins

80 pass for mounting the same on the clamps 3 adjacent the opposite end of the bed. The connection between the extensible link sections 10 and 11 embodies guide clips 14 carried by the upper end of the section 10 for 85 enclosing the link section 11 while the inner end of the link section 11 carries guide links 90 15 for enclosing the link section 10. As shown in Figs. 1 to 3 the link sections 11 are provided with openings 16 to receive pivot pins 17 carried by the levers 7, thereby

95 providing a pivotal connection between the link sections 11 and the levers 7.

The table top 9 embodies depending end plates 18 through which a pivot rod 19 passes for accommodating the upper ends of the levers 7 as shown in Figs. 1 and 2. An 100 angle slot 20 is formed in each end plate 18 and through which slots a rod 21 passes with the offset ends thereof received in the apertured lugs 22 carried by the upper ends of the link sections 11.

When the table 9 is in the operative position shown in Fig. 1 the link sections 10 and 11 of the extensible support lie adjacent each other with the rod 21, connected to the outer ends of the link sections 11, positioned at 110

the outer end of the angle slots 20 in the depending plates 18, the pivotal connection between the levers 7 and the sections 11 of the link members providing a substantial 5 mounting for the table top. The height of the table relative to the bed may be controlled by shifting the clamps 3 upon the side rails 1 while the position of the table relative to the ends 2 of the bed may also 10 be changed.

When it is desired to displace the table from the position overlying the bed, to its 15 inoperative position, the table top 9 is grasped and moved in a direction to extend the link sections 10 and 11 with the levers 7 moving on their pivotal connections 8 with the supporting clamps 3 and when so 20 position, the table top 9 is moved to a perpendicular position to cause the bolt 2 to travel in the angle slot 30 and be supported at the opposite end thereof as shown by dotted lines in Fig. 1. In this position the table top 9 is completely displaced from the bed with the supporting structure in no manner 25 interfering with the use of the bed for sleeping purposes.

While there is herein shown and described the preferred embodiment of the present invention, it is nevertheless to be understood 30 that minor changes may be made therein without departing from the spirit and scope of the invention as claimed.

What is claimed as new is:—

1. A table attachment for beds comprising 35 a plurality of clamps attached to the side rails of a bed, levers pivoted to the clamps adjacent one end of the bed, extensible link members pivoted to the clamps adjacent the other end of the bed, a table top pivotally 40 secured to the upper ends of the levers and extensible link members, said levers being pivoted to the extensible section of the link members with the table top moved to a position adjacent one end of the bed when the 45 link members are extended.

2. A table attachment for beds comprising 50 a plurality of clamps attached to the side rails of a bed, levers pivoted to the clamps adjacent one end of the bed, extensible link members pivoted to the clamps adjacent the other end of the bed, a table top pivotally 55 secured to the upper ends of the levers and extensible link members, said levers being

pivoted to the extensible section of the link members with the table top moved to a position adjacent one end of the bed when the link members are extended, the connection between the extensible link members and the table top being shiftable to permit the table top to assume a perpendicular position when out of use. 55

3. A table attachment for beds comprising 60 a plurality of clamps attached to the side rails of a bed, levers pivoted to the clamps adjacent one end of the bed, extensible link members pivoted to the clamps adjacent the other end of the bed, a table top pivotally 65 secured to the upper ends of the levers and extensible link members, said levers being pivoted to the extensible section of the link members with the table top moved to a position adjacent one end of the bed when the link members are extended, the connection between the extensible members and the table top including depending end plates 70 carried by the table top and movably associated with said link members to permit the table top to assume a perpendicular position when out of use. 75

4. A table attachment for beds comprising 80 a plurality of clamps attached to the side rails of a bed, levers pivoted to the clamps adjacent one end of the bed, extensible link members pivoted to the clamps adjacent the other end of the bed, a table top pivotally 85 secured to the upper ends of the levers and extensible link members, said levers being pivoted to the extensible section of the link members with the table top moved to a position adjacent one end of the bed when the link members are extended, the connection between the extensible members and the table top including end plates 90 depending from said table top and having angle slots therein, and a cross rod carried by the upper ends of said extensible members shiftable mounted in said slots to permit the table top to assume a perpendicular 95 position when out of use.

In testimony whereof I affix my signature 100 in presence of two witnesses.

STANISLAW KUCZYNSKI.
